CLAIM

The ornamental design for the brain sensing headband, as shown and described.

DESCRIPTION

FIG. 1 is a front perspective view of the brain sensing headband.

FIG. 2 is a front plan view of the brain sensing headband.

FIG. 3 is a right side plan view of the brain sensing headband.

FIG. 4 is a back plan view of the brain sensing headband.

FIG. 5 is a top plan view of the brain sensing headband; and,

FIG. 6 is a bottom plan view of the brain sensing headband.
